UNITED STATES PATENT OFFICE.

VALENTINE PICKLO, OF JOHNSTOWN, PENNSYLVANIA, ASSIGNOR OF ONE-HALF TO
GREGOR WALAT, OF JOHNSTOWN, PENNSYLVANIA.

CAR COUPLING.

Application filed February 16, 1922. Serial No. 536,997.

To all whom it may concern:

Be it known that I, VALENTINE PICKLO, a citizen of the United States of America, residing at Johnstown, in the county of 5 Cambria and State of Pennsylvania, have invented certain new and useful Improvements in Car Couplings, of which the following is a specification.

This invention relates to certain new and 10 useful improvements in railway draft appliances, and has particular reference to the production of an improved means for the coupling of railway cars.

The primary object of the invention is to 15 provide a car coupling device for railways wherein the construction is extremely simple and durable as well as efficient in operation.

Another object of the invention is to generally 20 simplify an improved device of this character and to provide means for cushioning the movement of the coupler of one car with respect to the adjacent coupler of the other car so that shocks and jars will 25 be taken care of, both in coupled and uncoupled positions.

With the above general objects in view the invention consists of the novel combination and arrangement of parts hereinafter 30 more fully described in connection with accompanying drawing, and in which like reference characters designate corresponding parts throughout the several views.

In the drawings:—

35 Figure 1 is a fragmentary view partly in top plan and partly in horizontal section of the adjacent ends of railway cars equipped with couplers in accordance with the present invention and with the couplers operatively engaged with each other;

Figure 2 is a view similar to Figure 1 of one of the couplers in released position;

Figure 3 is a fragmentary end elevational view of a car equipped with a coupler constructed in accordance with the present invention and shown in locked position, and

Figure 4 is a side elevational view of the device shown in Figure 3.

Referring more in detail to the several 50 views, in Figure 1 two adjacent cars A and B are shown with draw bars 5 having coupling heads 6 constructed in accordance with the present invention and adapted for cooperating so as to communicate movement of 55 one bar to the other.

The heads are of similar construction and have the same form of mechanism so that the description of one will suffice. As shown, each head 6 is of forked construction with one leg 7 longer than the other 60 leg 8 and having a jaw member 9 of angular form pivoted thereto for horizontal swinging movement upon a vertical axis 10 located at the outer end of the arm or leg 7. The central portion of the end of the head 6 is recessed to provide a pocket as at 11 into and out of which the inwardly extending arm of the member 9 is movable, so that when the arm is positioned within said pocket 11 the other arm of the jaw is 65 directed transversely of the longitudinal axis of the draw bar 5 in position to engage behind the similar arm of the jaw of the adjacent car coupling head as shown clearly in Figure 1. 70

The head 6 is provided with a vertical passage as at 12 substantially centrally of the same and communicating with the pocket 11 as well as adapted for removable reception of a key or pin 13 which, when positioned 75 in the passage 12 will engage the inner end of the inwardly extending arm of the jaw and hold the latter in coupling position.

The smaller or shorter leg 8 of the coupling head is provided with a socket 14 in 80 which is positioned a spring pressed plunger 15 having suitable means for limiting its outward movement and adapted to engage the adjacent portion of the laterally extending jaw of the other car coupling head 85 so as to cushion the movement of said jaw toward said leg 8. It will thus be seen that the laterally extending legs or arm of the jaws of adjacent coupling heads will be provided with a spring pressed plunger for 90 cushioning purposes. Each coupling head has another spring pressed plunger 16 which is slidably mounted in a suitable socket provided at an oblique angle in the inner end of the inwardly extending arm of the jaw 95 so as to cushion the movement of the coupling heads toward each other when the jaws 9 are in released position as shown in Figure 2, the free ends of the laterally extending arms of the jaws being then positioned to engage the plunger 16 of the other coupling head. 100

The jaw 9 is attached to a downwardly projecting strap iron 17 at a point outwardly of the pivot 10, and this arm is of angular 110

form so as to provide a rearwardly extending arm portion 18 connected to the horizontal member 19 of an angular lever by means of a link 20, said angular member including 5 a vertical portion 20 extending upwardly from the horizontal portion 19 and a transversely extending portion 21 terminating at a point near one side of the car and slidably mounted in suitable guides 22. The horizontal portion 21 may be provided with handle members 23 upon their outer ends for convenience in swinging the jaws 9 to open or closed position.

In operation, with the parts disclosed as 15 in Figure 1, the pins 13 of the adjacent coupling heads are removed, and the angular lever 19 is forced inwardly toward the draw bar 5 of each coupling head so as to swing the jaws 9 to inoperative or open position as 20 shown in Figure 2. The cars are then brought closer together so that the laterally extending arm of one jaw will lie inwardly of the similar arm of the other jaw, whereupon the levers 21 are pulled outwardly so as to swing 25 the jaws to locked or closed position as shown in Figure 1 whereby the laterally extending arms of said jaws are engaged behind each other. The plungers 16 and 17, during the operation, will effectively cushion the members for relieving considerable of the shock 30 usually experienced, and the pins 13 are then inserted downwardly through the passages

12 so that the jaws are effectively locked in closed or engaged position. It will be obviously apparent that the levers 21, 20, 19 35 cannot be operated to release the jaws until after the pins 13 are removed.

From the foregoing description, it is believed that the construction and operation 40 as well as the advantages of the present invention will be readily understood and appreciated by those skilled in the art.

Minor changes may be made without departing from the spirit and scope of the invention as hereinafter claimed. 45

What I claim as new is:—

The combination with a coupling head involving an angular pivoted jaw and a pair of legs, one longer than the other and to which said jaw is pivoted, the outer end of the shorter leg having a socket therein, the inwardly extending arm of said jaw having a socket therein, a cushion spring mounted in each socket, a plunger confined within the outer end of each socket and engaged by the spring, the plunger in said inwardly extending arm of the jaw being positioned at an angle to the plunger in said shorter leg whereby the first mentioned plunger is substantially parallel with the other plunger 50 when the angular pivoted jaw is in its open inoperative position for purposes specified. 55

In testimony whereof I affix my signature.
VALENTINE PICKLO.
